Primary Examiner—Caron D. Veynar
Attorney, Agent, or Firm—Wolf, Greenfield & Sacks, P.C.[57] CLAIM

The ornamental design for a utensil handle, as shown and described.

DESCRIPTION

FIG. 1 is a side, bottom perspective view of the utensil handle showing our new design;

FIG. 2 is a top view thereof;

FIG. 3 is a bottom view thereof;

FIG. 4 is a right side view thereof;

FIG. 5 is a left side view thereof;

FIG. 6 is a rear view thereof; and,

FIG. 7 is a front view thereof.

The broken line showings in FIGS. 1-7 are for illustrative purposes only and form no part of the claimed design.
